UNITED STATES PATENT OFFICE.

HIRAM G. SEDGWICK, OF MILL VALLEY, CALIFORNIA.

AUTOMATIC ELECTRICAL TRAIN-STOP.

No. 852,627.

Specification of Letters Patent.

Patented May 7, 1907.

Application filed November 24, 1905. Serial No. 288,915.

To all whom it may concern:

Be it known that I, HIRAM G. SEDGWICK, a citizen of the United States of America, and a resident of Mill Valley, county of Marin, State of California, have invented certain new and useful Improvements in Automatic Electrical Train-Stops, of which the following is a full and clear specification, reference being had to the accompanying drawings, in which—

Figure 1 is a diagrammatic view of a locomotive provided with my present improvements; Fig. 2 a detail longitudinal section of the fluid operated vent-valve; Fig. 3 a detail plan view of the piston-like vent-plug; Fig. 4 a vertical section of the locomotive showing more particularly the duplicate arrangement of the brushes and contacts; Fig. 5 a vertical section through the mechanism for operating the vent-valve and the reversing-switch on the locomotive; Fig. 6 a diagram showing the circuits, switches and contacts constituting one of the blocks; and Figs. 7, 8, 9, 10, 11, 12, 13, 14, and 15 a series of views showing various applications of the invention.

These improvements have special relation to that type of train-stopping apparatus and system covered by my co-pending application serially numbered 288,914, and filed Nov. 24, 1905 in which a valve connected to the train-pipe of the brake mechanism is vented automatically by means on the roadbed when the train approaches a danger point on the line, the venting of the train-pipe causing the air-brakes to be actuated in the same manner as when vented by the engineer, with his controller-valve, for a service stop.

In the present construction, as in the construction covered by the aforesaid application for patent, electrical mechanism is used for actuating the vent-valve, this mechanism being operated automatically by the coming together of contacts carried by the locomotive and contacts on the roadbed, a special arrangement of contacts on the locomotive and on the roadbed and suitable circuits and switches being employed.

In the present apparatus, as in the one covered by my co-pending application above referred to, means are employed whereby each train as it proceeds on its journey protects itself in rear as well as in front by successively bringing into action a series of pairs of contacts, so that collisions will be

avoided by each train pre-empting a block or section of the track as it proceeds.

An object of the present invention is to provide an improved form of vent-valve which may be operated by fluid pressure, either by steam from the locomotive or by air from the air-pipes of the brake system, as more fully hereinafter set forth.

Another object of the present invention is to provide improved means whereby the reversal of the direction of movement of the locomotive will automatically cut out the brushes at one side of the locomotive and bring into action the brushes at the other side, whereby the locomotive will protect itself irrespective of the direction in which it is going.

Another object of the invention is to provide simple means whereby the automatic stopping mechanism will be put out of action when the engineer cuts out his controller-valve, this cutting out of the controller-valve being done when the engine is running behind one or more engines, in which case it is the rule to put the control of the brake apparatus entirely in the hands of the engineer in the first locomotive, as more fully herein-after set forth.

Another object of the invention is to provide a more elaborate arrangement of the roadbed contacts and circuits whereby an increase in safety is obtained, in that in case of derangement of any of the circuits or switches a train will be stopped on entering that particular block, as more fully herein-after set forth.

Referring to the drawings annexed by reference-characters the letter *a* designates the train-pipe of the usual air-brake mechanism; *b* the usual storage reservoir; *c* the usual pipe leading from said reservoir to the engineer's valve *d* and thence to the train-pipe, by which the supply of air to the train-pipe is kept at normal pressure; *e* is a pipe connecting the train-pipe to the engineer's valve through which pipe *e* the train-pipe is vented the air escaping through a port *f* in the valve in the usual manner; *g* is a double cut-off in pipes *e* and *c*, at a point below the valve *d*, by means of which said valve *d* may be cut-off from the brake apparatus and rendered incapable of affecting the brake mechanism. All the above parts are constructed in the usual manner. The cut-off valve *g* is used to cut out the controller-valve when the locomotive is attached to a train behind one or

more preceding locomotives, in which case it is the rule for locomotives to cut out their brake-controlling means completely so that the leading locomotive will have complete control of the brake mechanism. Now, in order that my automatic brake mechanism shall also be cut out when the locomotive is running second or third, I connect my automatic vent-valve *h* to the vent-pipe *e* by means of a pipe *i*, so that when the engineer's valve is cut out my automatic mechanism will also be rendered inactive. Thus connecting my automatic vent-valve has the further advantage that the automatic stopping mechanisms will be rendered inactive on all the locomotives attached to the train except the first one, so that when the leading locomotive sets the safety-contacts behind it, in the manner hereinafter set forth, those active contacts will not affect the other locomotives in the train. This is necessary in order to prevent the air-brake mechanism from being automatically set by a locomotive running second or third or at the rear end of the train.

The vent-valve shown herein consists of a cylinder *j* in which a piston-like valve *k* fits and slides, this piston being provided with a transverse slot tapering from its forward end to its rear end. The air-pipe *i* connects to the cylinder *j* at a point opposite an opening *l* in the cylinder, so that when the piston *k* is pushed forward the tapering slot therein will put the pipe *i* in communication with the opening *l* and thereby vent the brake pipes. The tapering form of the opening or slot insures a gradual escape of the air thereby putting the brakes on gradually, in the manner of a service stop in contradistinction to an emergency application.

A spring *m* normally forces the piston back against the rear head of its cylinder and thus closes the opening *l*. A pipe *n* connects the rear end of the cylinder with the air-pipe *i*, and in an extension *o* of the cylinder *j* is inserted a rotating plug-valve *p*, which when rotated admits air under pressure to the rear end of the cylinder and thereby actuates the piston therein. Any other fluid may be employed to actuate the piston, as for instance steam which may be drawn from the steam-dome of the locomotive boiler. To permit the air from the rear end of the cylinder to escape and thus allow the piston to be automatically returned to a closed position, a suitable opening or a pet-cock *q* may be located between the rear end of the piston and the valve *p*.

To turn the plug-valve *p* I may employ any suitable mechanism, such for instance as is shown in my former patent No. 757,571, dated April 19, 1904, and this operating mechanism may be controlled magnetically substantially in the same manner as in my co-pending application hereinbefore referred to. In this controlling mechanism is em-

bodied an electro-magnet *r* which is in circuit with a pair of contact-fingers *s* mounted on a rotatable disk *t* which also carries a contact-bridge *u*. The contact-fingers *s* are adapted to alternately make contact with insulated contacts forming the terminals of two pairs of conductors *v*, which conductors lead to opposite sides of the locomotive where they are connected respectively to a pair of insulated brushes *w*. The bridge-piece *u* is adapted to alternately contact with two pairs of contacts which are respectively connected to conductors *x* and *y* which lead to duplicate pairs of contact-brushes *z* at opposite sides of the locomotive. This arrangement of circuits and switch is the same as in my aforesaid co-pending application, and the switch in the present instance is shifted so as to throw the current into one set of brushes or the other by axle-operated means instead of by means connected to the reversing-lever of the locomotive. Depending from the shaft of the switch-disk *t* is an arm *A* which carries a depending finger *B* which has a limited swinging motion on said arm *A* and whose lower end depends into the path of a tappet *C* carried by one of the axles of the locomotive, whereby when the axle rotates it will strike the part *B* and thereby shift the switch.

When the arm *A* is shifted to its limit in either direction, the finger *B* falls back into a vertical position where it hangs loosely, whereby it will permit the tappet *C* to freely pass it while the axle is rotating in the same direction but will positively engage the tappet *C* when the axle is rotated in the opposite direction. The shifting of this switch throws the current into the circuits at one side or the other of the locomotive as in my former application, and the only feature I claim in this application is the means for operating it through the instrumentality of the axle.

With regard to the roadbed devices and circuits I employ substantially the same devices that are shown in my former application hereinbefore referred to except that instead of having the safety-contacts *a'* normally dead or inactive means are provided in the present system whereby these contacts are kept normally alive or active, and another pair of contacts employed for cutting out these normally alive contacts provided no train is in the block, this arrangement being desirable out of abundance of precaution, since it will insure the automatic stopping of a train in case the mechanism of the block is out of order.

As in my former application, the contacts on the roadbed are arranged in series or groups, the safety-contacts *a'* being arranged at the beginning of each block, the setting-contacts *b'* being arranged a short distance ahead of the contacts *a'*, and the restore-contacts *c'*

being arranged at the end of the block. In Fig. 6 the contacts are arranged for a single-track road, one set being arranged at each side of the roadbed so as to be operated by 5 trains going in either direction. At the beginning of each block is conveniently placed a relay or switch-box d' preferably mounted on the usual telegraph-poles adjacent to the roadbed, and these boxes are connected by 10 two line-wires e', f' . The restore-contacts c' at the end of a block and also the safety-contacts a' and the setting-contacts b' at the beginning of the same block are connected by wires to one of the relay boxes, but any 15 other suitable arrangement of circuits may be employed.

The safety-contacts are connected by wires g' through a switch h' to a battery i' , said switch being adapted to be closed by a magnet j' and to be opened by a magnet k' . When the switch h' is closed the safety-contacts are alive and when the switch is open, as shown in Fig. 6, the contacts are dead, that is are cut out from the battery i' .

25 The setting-contacts b' are connected by wires l' to a battery m' , one limb of the circuit passing through the magnet of a switch n' , this switch being preferably the ordinary telegraph-sounder. The lower contact of 30 this switch is connected to ground through the battery o' and the upper contact is connected to ground through a wire p' . The armature lever, which normally bears against the upper contact, is connected by a wire q' 35 with a switch r' , this switch being preferably the ordinary relay switch used in telegraphy. The wire q' passes through the magnets of this switch and becomes the line wire f' , which leads to the relay box at the other end 40 of the block and connects with the companion switch or relay r' in that box. The relay r' , when energized, closes the circuit t' of the closing magnet j' , the wires of this circuit being connected to the aforesaid battery m' .

45 In each relay box the above-described mechanism is duplicated, the opening magnet k' being connected by wires u' , to a relay switch v' and a battery w' , and one of the 50 wires x' of this relay being connected through the armature lever of a switch y' and a wire z' to ground, while the other wire a^2 of this relay goes out of the box and becomes the line wire e' leading to the companion relay switch 55 v' at the other end of the block. The magnet of the sounder-switch y' is connected in circuit with battery w' by the wires b^2 with the restore-contacts c' . The lower contact of each of the switches y' is connected to 60 ground through a battery c^2 .

With an arrangement of contacts etc. such as above described it will be observed that if the switch h' is closed and the safety-contacts a' thereby made the terminals of the 65 battery i' , a locomotive upon entering the

block will be automatically stopped by having its contact-brushes make contact with said safety contacts, since as said brushes make connection with the safety-contacts the current from the battery i' will actuate 70 the magnet e and thereby vent the brake-pipes, but when the battery i' is cut out the safety-contacts will be dead and will have no effect on the valve-operating mechanism on the locomotive.

75 Should the safety-contacts be dead the train will be permitted to pass along to the setting-contacts b' . When the brushes t on the locomotive pass over these contacts, said brushes being spaced apart the proper distance to make contact with both these contacts at the same time, the battery m' will be brought into action through the circuit wires l' and thus actuate the sounder-switch n' . The actuation of this switch n' throws the 80 battery o' into circuit of the relay r' and thus (by closing the circuit t') energize closing magnet j' , which closes switch h' and makes the safety-contacts a' alive, thereby closing the block at a suitable point behind the train. 85 After closing the circuit of magnet j' the current passes on through the line wire f' through the companion relay r' in the distant relay box and thence down through the armature lever of the switch n' and through 90 wire p' to ground. In passing through this latter relay switch r' the circuit t' of the magnet j' is closed, thus actuating switch h' and throwing the safety-contacts a' at the other end of the block into circuit of the other battery i' , thereby protecting the train at a pre-determined distance ahead of it from trains 95 coming in the opposite direction.

When the train reaches the restore-contacts c' , which are spaced the same distance 100 apart as the setting-contacts b' the same brushes that contacted with the contacts b' also make contact with these contacts c' , thereby closing the circuit b^2 in which is included the battery w' and the magnet of the 105 adjacent sounder-switch y' . Thus actuating the switch y' throws the current from battery c^2 up through the adjacent relay v' and thence back to the first relay box and through the companion relay v' to ground 110 through wire z' . In passing through the first-mentioned relay v' the circuit u' of wire k' is closed thus opening switch h' in the main branch of circuit $g' g'$. This restores 115 all the parts to their normal position, in which position the switches h' will be open and all the circuits will be open, thus avoiding waste of current and enabling a single set of batteries to last a great length of time. A train going in the opposite direction will, 120 after the initial safety-contacts a' are rendered inactive, operate to protect itself in the same manner, that is by throwing the safety-contacts at both ends of the block into circuit with their respective batteries, 125 130

and finally through the restore-contacts open the switches h' and leave the contacts in their normal condition. I have shown and described my system as adapted for 5 single-track railways, but it will be observed that without material modification it may be used on double-track roads, where it is only necessary to protect a train against trains going in the same direction.

10 In the system covered by my former application above referred to the safety or danger contacts a' were kept normally dead, whereas in the present modification of my system I provide simple means for keeping 15 these contacts normally alive so as to require each train as it enters the block to make these contacts inactive before it can enter the block, provided of course that no train has previously entered and pre-empted the 20 block. I do this by introducing a supplemental switch g^3 which is closed by a magnet l^3 which is in circuit with the setting-contacts b' and switch n' through a supplemental circuit l^2 . When this magnet l^3 is energized it 25 causes the switch g^3 to close a supplemental circuit g^2 connected to the circuit g' of the safety-contacts. This switch g^3 is opened automatically by an approaching train by means of a pair of supplemental-contacts m^3 30 which precede the safety-contacts and which are in circuit with battery i' and an opening-magnet n^3 . With this arrangement it will be observed that the passing of a train over setting-contacts b' not only closes main 35 switch h' but also closes the supplemental switch g^3 , so that the safety-contacts can be rendered inactive only by opening both these switches. It will be observed also that as the train passes over the restore-contacts c' 40 it will open only the switches h' leaving the switches g^3 closed and the safety-contacts alive. Thus it will be observed that before a train can enter a block it will have to open the switch g^3 , through the medium of the 45 supplemental contacts m^3 and magnet n^3 , before it can pass the safety-contacts which are of course but a short distance ahead of the supplemental-contacts. This provision for keeping the safety or danger contacts normally alive is advantageous in that if the apparatus is out of order, the train will be stopped, unless of course the disorder is in 50 the supplemental circuits g^2 and l^2 .

Referring to Figs. 11 and 12, leading from 55 the stopping-contacts are a pair of wires b^4 , which include a battery c^4 and are connected to the two contacts of a circuit-closer d^4 , one of these contacts being connected to a rock-shaft e^4 , which in turn is connected to the 60 semaphore by a link f^4 . With this construction when the semaphore-arm is raised to danger the switch d^4 will be closed thus throwing the battery into circuit with the roadbed contacts, so that should a locomotive 65 pass over these contacts the train would

be stopped automatically through contact-brushes $w w$. Thus connecting up the stopping-contacts with one of the usual forms of signals, it will be observed that the stopping-means is made supplemental to the signal 70 devices, so that in case the engineer fails to see the signal or attempts to disobey the command the signal communicates to him, the train will be stopped automatically.

In Figs. 13 and 14 this invention is shown 75 as applied to a drawbridge, suitable spring-actuated push-rods g^4 being so located that when the drawbridge is opened said rods will automatically close the switch d^4 . One of these devices is used at each end of the drawbridge so that the track will be blocked at 80 both sides of the drawbridge.

In Figs. 7 and 10 the invention is shown applied to a guard-fence carrying a wire h^4 , which is stretched the length of the fence in 85 such position that it will be displaced or ruptured in case the fence is broken by the falling of a boulder or any other object against the fence. The wire h^4 is connected at each of its ends to a double switch d^4 , which will 90 close the circuit whether the wire h^4 be broken or simply displaced or thrown down. In Fig. 9 the connecting-wire h^4 is stretched along a trestle and is connected to branch wires or guys h^{4x} , so that in case the trestle 95 or any part of its supports be injured or carried away, the main wire h^4 will be displaced sufficiently to close the switches d^4 , and thus render the contacts at each side of the trestle active.

It will be observed from the foregoing that this invention is adapted for use in connection with a great variety of roadbed appliances and that therefore I do not desire to be restricted in this respect.

It will be apparent to those skilled in the art that various mechanical embodiments of the invention are possible and I, therefore, do not wish to be limited to the exact arrangement and construction shown.

What I claim and desire to secure by Letters Patent is:—

1. A locomotive equipped with air-brake apparatus embodying an engineer's controlling-valve and a cut-off means between the same and the train-pipe, and an automatic venting device connected to the brake system at a point between the controlling-valve and the cut-off means, said automatic venting device embodying means adapting it to be operated only by roadbed devices.

2. A locomotive equipped with a brake system embodying duplicate contacts and circuits at opposite sides of the locomotive, a switch device, and axle-operated means for actuating this switch device consisting of a tappet on the axle and a depending shiftable arm carried by the switch and means whereby the tappet may pass the arm freely after it has shifted it.

3. A locomotive equipped with an air-brake apparatus embodying an electrically-controlled vent-valve and duplicate contact-brushes and circuits at the opposite sides of the locomotive, a switch, an axle-operated means for automatically shifting said switch for the purpose set forth, said means embodying an arm depending from the switch and carrying a swinging finger having a limited vibration, and a tappet on the axle.

4. In an electrical train-stopping block system, the combination of electrically-controlled means on the locomotive for applying the brakes, a series of stopping-contacts on the roadbed, means on the roadbed for keeping these contacts normally operative, and means on the roadbed ahead of these contacts whereby these contacts are successively rendered inactive by an approaching train if the block ahead be unoccupied.

5. In combination with a locomotive carrying electrically-operated train-stopping devices, of a roadbed block system each block embodying a pair of stopping-contacts and means for normally keeping these contacts active, a pair of contacts preceding said stopping-contacts to render them inactive, a pair of setting-contacts ahead of the stopping-contacts to set said stopping-contacts behind the locomotive, and a pair of restore-contacts and means connected therewith for restoring the parts to normal position, leaving the safety-contacts alive but subject to the control of the supplemental-contacts.

6. In combination with a locomotive provided with electrically-controlled train-stopping mechanism, a pair of stopping-contacts and means connected therewith for normally keeping them alive, said means embodying a main switch and a supplemental switch, a pair of preceding supplemental-contacts and means connected therewith for opening said supplemental switch, a pair of setting-contacts and means connected therewith for closing both of said switches, and a pair of restore-contacts and means connected therewith for opening the main switch without affecting the supplemental switch, substantially as set forth.

7. A roadbed train-stopping system, comprising a stopping device normally operative, a device on the roadbed preceding said stopping device and adapted to render the same inoperative, a setting device adapted to return said stopping device to its normally operative condition, and a restore device at the end of the block for restoring the devices to normal condition, substantially as set forth.

8. A train-stopping electrical system, embodying a series of contacts at either side of the roadbed, constituting a block, these devices being arranged reversely so as to control trains going in either direction, and each

series embodying a pair of supplemental-contacts, a pair of stopping-contacts, a pair of setting-contacts, a pair of restore-contacts, and electrically-controlled means whereby the stopping-contacts are kept normally active, the supplemental-contacts render the stopping-contacts inactive, the setting-contacts render the stopping-contacts again active, and the restore-contacts restore the parts to normal.

9. A roadbed block system, embodying a pair of stopping-contacts and means connected therewith for keeping them normally alive, these means embodying a main switch and a supplemental switch, means on the roadbed whereby an approaching train opens the supplemental switch, means on the roadbed whereby both switches are closed, and means at the end of the block for opening the main switch without affecting the supplemental switch.

10. In a block system for railways, the combination of a locomotive equipped with automatic brake devices embodying pairs of brushes, and roadbed devices consisting of a pair of contacts normally alive, supplemental devices ahead of these stopping-contacts for rendering them inactive, a pair of setting-contacts beyond the stopping-contacts and a pair of restore-contacts at the end of the block, and electrical connections whereby the passage of a train over the setting-contacts will return the stopping-contacts to normal active condition and prevent them being again rendered inactive by the supplemental devices ahead of the stopping-contacts, and means whereby the passage of a train over the restore-contacts will again render the stopping-contacts subject to the supplemental devices.

11. The combination with a locomotive carrying electrically-operated train-stopping devices, of a roadbed block system, each block embodying stopping devices and electric means for normally keeping these stopping devices active, electric means preceding said stopping devices and adapted to render them inactive if an oncoming train has not already preempted the preceding block, electric setting devices beyond said stopping devices to set said stopping devices behind the locomotive, and electric restoring devices and means connected therewith for restoring the parts to normal position, leaving the stopping devices active and subject to the devices for rendering them inactive.

In testimony whereof I hereunto affix my signature in the presence of two witnesses this 2d day of November 1905.

HIRAM G. SEDGWICK.
